THEODORE BIRNBAUM, OF LONDON, ENGLAND, ASSIGNOR TO VICTOR TALKING MACHINE COMPANY, A CORPORATION OF NEW JERSEY.

AUTOMATIC BRAKE FOR TALKING-MACHINES.

1,021,756.

Specification of Letters Patent.

Patented Apr. 2, 1912.

Application filed November 15, 1909. Serial No. 528,039.

To all whom it may concern:

Be it known that I, THEODORE BIRNBAUM, a subject of the King of Great Britain, and a resident of the city of London, England, 5 have invented certain new and useful Improvements in Automatic Brakes for Talking-Machines, of which the following is a specification.

The present invention relates to an improved automatic brake for gramophones and similar talking machines.

According to this invention a brake is provided which will automatically stop the machine when the selection has been played 15 and the brake may either be operated by putting sidewise pressure on the sound arm as it reaches the end of the selection, in the manner proposed with other known constructions of automatic brake, or this sidewise pressure may be dispensed with and the record furnished with an auxiliary spiral, in well known manner, running from the end of the sound line to a circular track around the center of the record.

25 A further feature of the invention is that the brake can be taken off, so as to start the machine running, by bringing the sound arm back to the starting position, that is the position which will bring the reproducing 30 needle to the commencement of the sound line.

My invention is illustrated in one form in the accompanying drawings.

Figure 1 is a plan view of part of a disk 35 talking machine fitted with the improved brake, the brake being shown in the off position. Fig. 2 is a similar view, but with the brake on. Fig. 3 is a side elevation of Fig. 2. Figs. 4 and 5 are side elevation 40 (partly in section) and plan respectively of the brake on an enlarged scale. Fig. 6 is a top plan view of a modified form of this invention, and Fig. 7 is a fragmentary front elevation of a portion of the same, looking 45 in the direction of the arrow in Fig. 6.

The sound arm *a* is carried in the usual way, pivoted in the bracket *b* which is fixed rigidly on the cabinet *c*. The sound box *d* is carried in the usual manner by the semi- 50 circular piece *e* jointed to the sound arm at *f*. The turntable *g* is shown carrying a record *h*. From the sound arm there extends downward a pin *i*, with a roller *i*¹ at its lower end. In the machine shown in the drawings, there is arranged within the sound

arm, at its bearing a coiled spring *j*, which tends to throw the sound arm across the record toward the center. One end of this spring is secured to the upper of the two cross pieces *j*¹ *j*² through which the bearing 60 pivot *j*³ passes, and after passing three or four times around the pin, the other end of the spring is fixed to the lower cross piece.

On the top of the cabinet *c* is screwed the plate *k*, and secured thereto, but so as to 65 be capable of lateral adjustment is the second plate *k*¹; upon the plate *k*¹ are pivoted so as to swing horizontally two levers; one *l*, turning about a pivot *l*¹ is furnished at one end with a brake pad *m*, which is pulled 70 against the side of the turntable *g* by the spring *n*, and at the other end the lever *l* is formed with a cam face *l*², (Fig. 5). The second lever *o*, turning about a pivot *o*¹, has three arms, one is furnished with a pin *p*, 75 which bears on the cam face *l*² of lever *l*, and may advantageously be provided with a roller to reduce friction, the second arm has a projecting finger *q* which normally stands in the path of the pin *i* on the sound arm, 80 and the third arm *r* is an extension by means of which the brake can be put into the off position by moving the sound arm outward or away from the center of the record. A spring *s* bears lightly on the lever *o* and 85 tends to hold the pin *p* up against the cam face *l*², when the brake is on.

The operation of the device is as follows: A record is placed on the turntable and the sound arm is moved outward away from 90 the record, into the position shown in dotted lines in Fig. 2. This brings the roller *i*¹ carried by the pin *i* up against the arm *r* so that it pushes back the latter into the position shown in Fig. 1 and so causes the pin 95 *p* to ride up the cam face *l*² of the lever *l*, and bring the brake pad *m* away from the turntable. The arm *r* is preferably made of such length that on the roller *i*¹ pressing it back to the full extent, the pin *p* will be 100 brought to rest on the top of the cam surface *l*², so as to remain there till displaced. The turntable having started on the removal of the brake pad *m*, the needle of the sound box is placed on the record, at the beginning of the sound line, the several parts of the apparatus now occupying the position shown in full lines in Fig. 1. As the needle follows the sound line, the sound arm 105 gradually approaches the center of the rec- 110

ord. On the needle reaching the end of the sound line the resistance of the sides of the sound groove is removed and the spring *j* throws the arm *a* farther toward the center 5 of the record. Just before the needle, sliding over the smooth unrecorded portion of the record, reaches the circular label in the center, indicated by *x* in the drawings, the roller *i*¹ strikes the projecting finger *q* on 10 the lever *o*, as shown in dotted lines in Fig. 1; this trips the lever *o*, and dislodges the pin *p* from its position, so that the lever *l* is released and the spring *n* pulls the brake pad *m* against the turntable *g*, and stops 15 the machine.

The record *h* is usually furnished with a slightly raised ridge *y* running around the central label, and this prevents the needle from being thrown by the spring *j* on to 20 the label. The possibility of this occurring may further be obviated by making the projecting finger *q* of such shape that when the needle has reached the ridge *y*, the roller *i*¹ lies against the point of the finger *q*, and 25 to pass it has to overcome the spring *s*. This spring *s* is so placed as not to press on the lever *o* when the brake is in the off position, but only when the brake is on and the lever *o* is in the position shown in Figs. 2 30 and 5.

If the sound arm is carried beyond the position shown in full lines in Fig. 2, then whether the brake is in the off position or in the on position, that is, in the position 35 shown in Figs. 1 or 2, the sound arm can always be returned to its starting position, for the outside face *q*¹ (Fig. 5) of the finger *q* is made beveled, so that the roller *i*¹ will ride up it and force the lever *o* back. In 40 the same way, if when the sound arm is brought out away from the record to the position shown in dotted lines in Fig. 2, the brake is put on and the arm *r* so brought again into the path of the roller *i*¹, the 45 sound arm can be returned to the position for playing a record, for the roller *i*¹ will ride up the beveled face *r*¹ (see Fig. 5). There is thus no risk of the sound arm striking the brake so as to damage it or 50 put it out of order.

The object of having the levers *l* and *o* pivoted on a plate which is adjustable on the cabinet is to allow of the accurate positioning of the brake with regard to the pin 55 *i* on the sound arm, without damaging the cabinet. The plate *k* is first secured to the cabinet so as to bring the lever *o* into approximately the correct position, and then, the exact position having been obtained, the 60 plate *k*¹ is clamped down on to the plate *k*.

It will be obvious that for playing records that are furnished with an auxiliary spiral groove or run out in well known manner, the spring pressure upon the sound 65 arm can be dispensed with. In this case

the runout spiral will draw the needle to the edge of the label when the selection is finished, and so cause the pin *i* to trip the lever *o*.

The brake may of course be made as 70 above described, but without the arm *r*; I prefer however to make it with this arm as the machine can then be started and the sound box brought into the correct position for commencing the reproduction by a single movement.

If it is preferred to dispense with the pin *i* in the sound arm, the lever *o* may be arranged to swing vertically, as shown in Figs. 6 and 7 and in this case will be tripped 80 by the sound arm itself. The cam surface *l*² in this construction would have to rise vertically, so that the pin *p* as it rose and fell might operate the lever *l*.

Having thus described my invention what 85 I claim as new and desire to secure by Letters Patent is:—

1. In a talking machine, the combination with a rotary record support, of movable sound reproducing means, means for braking said record support normally held in engagement therewith, controlling means actuated by the said reproducing means and movable about a fixed axis independently of said braking means and of said reproducing 95 means for rendering the braking means inoperative when said sound reproducing means is moved from an inoperative position to a starting position, and for bringing said braking means into operation as said sound reproducing means reaches the inner 100 end of its reproducing path.

2. In a talking machine, the combination with a rotary record support, of movable sound reproducing means, means for braking said record support normally held in engagement therewith, controlling means actuated by the said reproducing means and movable about a fixed axis independently of said braking means and of said reproducing 105 means for rendering the braking means inoperative when said sound reproducing means is moved inwardly from an inoperative position to a starting position, and for bringing said braking means into operation 110 as said sound reproducing means reaches the inner end of its reproducing path.

3. In a talking machine, the combination with a rotary record support, of movable sound reproducing means, means for braking said record support normally held in engagement therewith, controlling means actuated by the said reproducing means and movable about a fixed axis independently of said braking means and of said reproducing 120 means for rendering the braking means inoperative when said sound reproducing means is moved outwardly from an inoperative position to a starting position, and for bringing said braking means into operation 125 as said sound reproducing means reaches the inner end of its reproducing path.

130

as said sound reproducing means reaches the inner end of its reproducing path.

4. In a talking machine, the combination with a rotary record support, of movable sound reproducing means, means for braking said record support normally held in engagement therewith, controlling means actuated by the said reproducing means and movable about a fixed axis independently of said braking means and of said reproducing means for rendering the braking means inoperative when said reproducing means is moved either inwardly or outwardly from an inoperative position to a starting position, and for bringing said braking means into operation as said sound reproducing means reaches the inner end of its reproducing path.

5. In a talking machine, the combination with a rotary turntable, of sound reproducing means, a pivoted swinging arm carrying said sound reproducing means, a brake lever pivoted upon a fixed axis and having a brake shoe normally held in engagement with said turntable, a controlling lever pivoted upon a fixed axis spaced from the fixed axis of said brake lever and actuated by the movement of said sound reproducing means and movable independently of said arm, and means carried by and projecting from said arm and adapted to engage said controlling lever to render said brake lever inoperative when said sound reproducing means is moved from an inoperative position to a starting position.

6. In a talking machine, the combination with a rotary turntable, of sound reproducing means, a swinging pivoted arm carrying said sound reproducing means, braking means normally engaging said turntable, a controlling lever pivoted upon a fixed axis, and normally out of engagement with said arm but actuated by the movement of said arm in one direction, first to render said braking means inoperative and then to render the same operative, said controlling lever being actuated by the movement of the said arm in the opposite direction to render said brake inoperative.

50 7. In a talking machine, the combination with a rotary record support, of movable sound reproducing means, braking means for said turntable, and means operatively connected only at predetermined intervals to be actuated by the movement of said sound reproducing means in one direction, first to render said braking means inoperative and then to render the same operative, and rendered inoperative by the movement of said sound reproducing means in the opposite direction.

8. In a talking machine, the combination with a rotary turntable, of movable sound reproducing means, braking means for said turntable, and controlling means operatively

connected at predetermined intervals to be actuated by the movement of said sound reproducing means either inwardly or outwardly with respect to said table adjacent the starting point of said sound reproducing means for rendering said braking means inoperative, said controlling means being retained in inoperative position independently of said reproducing means.

9. In a talking machine, the combination with a rotary turntable, of movable sound reproducing means, braking means for said turntable, and controlling means normally free from said sound reproducing means but operatively connected at predetermined intervals to be actuated by the movement of said sound reproducing means either inwardly or outwardly with respect to said table adjacent the starting point of said sound reproducing means for rendering said braking means inoperative, said controlling means being also actuated by the inward movement of said sound reproducing means adjacent the inner end of its path to render said braking means operative.

10. An automatic brake for gramophones and similar talking machines comprising in combination a turntable, a horizontally swinging brake lever, a brake pad at one end of said lever, a cam face at the other end of said lever, a spring for normally holding the brake pad in engagement with said turntable, a two-armed horizontally swinging tripping lever, one arm of which lever carries a pin which bears against and rides on the cam face on the brake lever for the purpose of removing the brake pad from the turntable, and for releasing the brake pad to move into engagement with the turntable.

11. An automatic brake for gramophones and similar talking machines comprising in combination a turntable, a movable sound box arm, a horizontally swinging brake lever, a brake pad at one end of said lever a cam face at the other end of said lever, a spring for normally holding the brake pad in engagement with said turntable, and a two-armed horizontally swinging tripping lever one arm of which lever carries a pin which bears against and rides on the cam face on the brake lever for the purpose of removing the pad from the turntable while the second arm of the tripping lever is formed so as to be tripped by said sound box arm when the sound box arm approaches the end of its operative path for the purpose of bringing the brake pad into engagement with the turntable and thus stopping the machine.

12. An automatic brake for gramophones and similar talking machines comprising in combination a turntable, a movable sound reproducer, a horizontally swinging brake lever, a brake pad at one end of said lever, a spring normally holding said pad in en-

- gagement with said turntable, a two armed tripping lever swinging about a fixed vertical axis, means for removing the brake pad from the turntable when said reproducer is placed in the starting position, and for releasing the brake pad to move into engagement with the turntable as said reproducer approaches the end of its operative path across said turntable.
- 10 13. An automatic brake for gramophones and similar talking machines comprising in combination a turntable, a movable sound reproducer arm, a horizontally swinging brake lever, a brake pad at one end of said lever and a cam face at the other end of said lever, a spring normally holding the brake pad in engagement with said turntable, and a horizontally swinging tripping lever of which one arm, carrying a pin, lies in the path of said sound reproducer arm as it is returned to the starting position so that this movement will force the pin to bear against and ride on the cam face on the brake lever and bring the brake pad away from the turntable while a second arm on said tripping lever is formed so as to be tripped by the sound reproducer arm as said sound reproducer arm approaches the end of its operative path across said turntable.
- 15 30 for the purpose of bringing the brake pad into engagement with said turntable.
14. In a talking machine, the combination with a rotary record support, of a movable sound reproducer arm, a pin carried by said arm, means movable about a fixed axis for braking said record support, and means actuated by said pin and embracing said pin, between predetermined limits of the path of said pin, and movable about a separate fixed axis independently of said braking means and of said sound reproducing means, for controlling said braking means.
15. In a talking machine, the combination with a rotary record support, of movable sound reproducing means, and means for braking said record support and controlling means actuated by said reproducing means and movable about a fixed axis independently of said braking means and of said

sound reproducing means for maintaining 50 said braking means in inoperative position.

16. In a talking machine, the combination with a rotary record support, of movable sound reproducing means, comprising a projection, braking means operative to stop said support, and brake controlling means embracing said projection and operative to be shifted by engagement therewith to actuate said braking means, said brake controlling means being shifted to render said brake 60 operative by the movement of said reproducing means in one direction and arranged to render said braking means inoperative by a movement in either direction.

17. In a talking machine, the combination 65 with a turn-table, of a pivoted swinging arm carrying sound reproducing means, a brake lever pivoted upon a fixed axis, means tending to shift said lever into engagement with said turn-table, and a separate brake controlling lever pivoted upon a separate fixed axis and actuated by the movement of said swinging arm to release, or to retract said brake lever, or to retain said brake lever inoperative independent of the position of 75 said arm.

18. In a talking machine, the combination with a turn-table, of movable sound reproducing means, braking means operative to stop said turn-table, and controlling means 80 movable independently of said reproducing means and said braking means, and actuated by the movement of said sound reproducing means either inwardly or outwardly with respect to said turn-table adjacent to the starting point of said sound reproducing means for rendering said braking means inoperative, said controlling means being retained in either its operative or inoperative positions independently of 85 90 said reproducing means.

In testimony whereof I have signed my name to this specification in the presence of two subscribing witnesses.

THEODORE BIRNBAUM.
